Application July 22, 1939, Serial No. 285,888
In the Netherlands July 23, 1938

4 Claims. (Cl. 250—40)

This invention relates to a wireless receiver for reception of a plurality of wave length ranges which is capable of being automatically tuned to a number of predetermined stations by means of a station selector constituted, for example, by a keyboard. Such a station selector greatly facilitates tuning since for tuning to a given station it is only necessary to press the member associated with that station such, for example, as a key with the result that the tuning condenser reaches automatically the tuning position of the said station. Since, however, the stations to be selected by the station selector are distributed about a plurality of wave length ranges, generally 15 about the long wave and the intermediate wave regions, it is necessary for the user always to operate the wave length switch as well, which involves a complication in the control of the set. This disadvantage is obviated by the present invention.

The wireless receiving set of the kind described above is characterized in that the said keys also cooperate with the wave length switch present in the set in such manner that upon operation of some key the set is suitable for reception on the wave length range corresponding to the said key. So the operation of the wave length switch as a supplementary operation in tuning to a station by means of the station selector prior to the operation of a key is entirely omitted. Tuning is thus rendered substantially simple.

The arrangement may be carried into practice in a great variety of ways. Thus, for example, according to the invention it is possible to provide each of the keys with one or more stops capable of being adjusted relatively to the operating mechanism of the wave length switch, the wave length switch being caused to occupy the desired position while the key concerned is being forced in or subsequently to that, through the cooperation of the said stop or stops and the said mechanism. In such a construction it is possible in various ways to construct the stop or stops to be adjustable. Thus, for example, it is possible to constitute the stop by a stylus or other member capable of being disengaged from the key and of occupying various positions relatively to the key and also relatively to the operating mechanism of the wave length switch due to the presence of a plurality of apertures in the key. In a further embodiment the stop will always occupy a stationary position relatively to the key and adjustment of the key to another wave length range is effected by rotation of the key about its long 55 axis.

The cross section of the said stop may be wedge-shaped in such manner that on the key being forced-in the stop pushes away the operating member of the wave length switch. The operating mechanism of the wave length may be 5 shaped in different forms.

In a convenient embodiment of the set according to the invention the operating mechanism of the wave length switch is slidable and moves the wave length switch into the desired position by 10 the shifting consequent upon the engagement of the stop by the forced-in key. A very compact form of construction is obtained in a further embodiment in which the center lines of the keys follow a straight line in parallel with which the 15 operating mechanism of the wave length switch is arranged, said mechanism being capable of performing not only a shifting endwise, but, due to its journalling, also a swinging movement normal to the sliding movement and being provided 20 with projections, the arrangement being such that due to its previous shaping and moving possibility this member is also capable of maintaining the forced-in key in its forced-in position.

In a further embodiment in which each of the 25 keys described above is provided with a removable member and in which the keys are arranged on a row a number of rails corresponding to the number of wave ranges to be covered is arranged parallel with the said row in such manner that 30 the ends of the removable stops cooperate, in each of their positions in one of the keys, with one of the said rails. In this case each of the rails may be united to a lever which moves the wave length switch into the desired position. 35 The keys will generally be arranged in a straight line but it is also possible to arrange them to follow a curved line, the busbars being curved in a corresponding manner.

In a further embodiment the end of each of 40 the stops in each of the keys cooperates with a change in profile of a member arranged parallel with the keys so that forcing-in of one of the keys in accordance with the position of the stop or stops has the effect of shifting the said member 45 and thus of changing the wave length switch.

In a further embodiment the operating mechanism of the wave length switch is formed by a scissor shaped member whose blades have correlated movements, for example by means of gear 50 wheels, and are arranged side by side, the arrangement being such that by adjustments of the member in one of the keys which cooperates with the said mechanism, this member engages either the one or the other blade.

In order that the invention may be clearly understood and readily carried into effect it will now be described more fully with reference to the accompanying drawings.

5 Figs. 1, 2, 3, and 4 show one form of construction of the device according to the invention; Figs. 5 and 6 illustrate diagrammatically another form of the invention using a different type of switch control; Fig. 7 illustrates a modification of the invention using a displaceable rocker bar; Figs. 8, 9 and 10 are different views of a system constructed according to the invention and employing a plunger type of switch control device; 10 Figs. 11 and 12 illustrate a modification of the invention wherein lateral displacement of the switch control mechanism is produced; and, Fig. 13 illustrates a modification of the invention employing a scissors type of switch control.

15 20 The shaft 1 which carries the rotary part of a tuning condenser has mounted on it a pinion 2 which engages a toothed sector 3 which can be moved by a lever 4 pivoted at 5. This lever is always forced upwardly by the action of a spring 25 25 6. This lever is engaged by the end of the shaft 7 of a key 8. The part 9 which is adapted to rotate in the shaft 7 may be lengthened or shortened by means of a set screw 10 and thus permits of varying the rotation of the shaft 1 30 and hence the tuning when the key 8 is forced-in.

A wireless set generally comprises a number of such keys, said keys corresponding generally to the stations in various wave length ranges. By adjusting the part 9 the user of the set can 35 himself always determine which stations he desires to receive automatically by means of the keys by forcing-in the key concerned. The presence of the device described hereinafter which, upon a key being forced in, moves the wave 40 length switch into the position associated with the station selected avoids the need for moving the wave length switch as a supplementary operation in addition to forcing-in a key.

This device comprises a stop 11 which, when 45 the set can be switched to stations in two wave length ranges, can be inserted in one of the two apertures 12 and 13 that are formed in the key-shaft 7. These apertures are clearly shown 50 in Fig. 4, which is a side view of the key 8 and the key-shaft 7. Fig. 1 shows the stop 11 inserted in the aperture 13 and in dotted lines the manner in which the stop 11 can be inserted in the aperture 12.

Whereas in Fig. 1 the key 8 is shown at rest, 55 Figs. 2 and 3 show this key in forced-in position, the stop 11 having engaged one of the arms 14 of a bell crank which is pivoted at 15 and the other arm 16 of which is connected to the wave length switch (not shown), for example by means of a 60 Bowden cable 17. A comparison of Figs. 2 and 3 reveals that when the stop 11 is inserted in the aperture 13 the bell crank turns through a substantially larger angle α than when the stop 11 is inserted in the aperture 12 with the result that 65 the lever has turned through an angle b . Due to this difference in angle values the wave length switch occupies a different position in the two cases so that the effect desired is obtained. For the sake of completeness this figure shows in addition the device by means of which the key maintains its forced-in position. For this purpose the key shaft 7 has secured to it a truncated member 18 which, when the key is forced-in, is maintained in this position by a lever 19 which locks the member 18 under the pull of a retract-

ing spring 20. When a further key is forced-in the member 19 is unlocked and the forced-in key is again raised under the action of a compression spring 21.

A further embodiment is illustrated in Figs. 5 and 6 in which only two press buttons 22 and 23 are shown for the sake of clearness, said press buttons comprising a locking device 24 which is similar to that shown in Figs. 1 and 2 and for this reason will not be described here in greater detail. The key-shafts 25 and 26 carry a wedge-shaped member 27, 28 which will always occupy a stationary position relatively to the key-shaft 25 and 26 but are enabled, by a rotation of the keys 22 and 23 through 180°, to occupy a different 15 position relative to the operating mechanism 29 of the wave length switch. This operating member comprises a strip 30 which has formed in it apertures 31 which are situated below the members 27 and 28. The strip 30 is maintained in 20 its mid-position under the pull of two retracting springs 32 and 33. When a key as, for example, the key 23 of Fig. 6 is forced in the wedge-shaped member 28 engages the side 34 of the aperture 31 and on the key being forced into a further extent it pushes the strip 30 to the right. This has the effect of also moving a projection 35 on the strip 30 to the right and of thus pushing to the right the arm 36 of the switch thus connecting arm 36 to right-hand contact of the wave change 30 switch 37. As soon as the key 23 returns to its off-position the strip 30 moves again to its mid-position under the pull of the springs 32 and 33. Obviously, on the key 22 being forced-in the strip 30 is moved to the left with the result 35 that the switch arm 36 is connected to the left-hand contact of the wave length switch. As stated before, the wave length switch is changed over to the other side when one of the keys 22 and 23 is rotated through 180° about its long axis. 40

The keys have naturally to be arranged in such manner that they cannot be rotated by accident. This may be ensured by suitable locking. Thus, for example, it is possible to construct the knobs of the keys, so as to be square and to bring them 45 together very closely so that the keys provide themselves for locking against rotation of the neighboring keys.

Fig. 7 shows the system of Figs. 5 and 6 except that the locking device 24 and the wave length 50 switch operating mechanism are united to form a single member. For this purpose the member 40 not only is rotatable on the shafts 38 and 39 according to the arrow A but is also slidable on them endwise according to the arrows B. Each 55 of the keys of which only two, 41 and 42, are shown in the figure is provided with a member 43 and 44 which is shaped in the form of a truncated cone severed along its long axis. When the key 41 is forced-in the member 43 engages the left 60 hand side 45 of an aperture 47 formed in the lower portion 46 of rocking member 40. The member 40 is thus moved to the left so as to slide on the shafts 38 and 39. At the same time the rear-side of the member 43 has been shifted on 65 the inclined part 48 of the rocking member and has thus moved this rocking member backwards with the result that the edge 49 of the recess 47 clasps the upper side of the member 43, which is also due to the action of a compression spring 70 50. This ensures locking of the key 41, while at the same time the displacement to the left mentioned before of the rocking member causes the contact 54 to engage contact 55. It should be noted that contact 54 is mounted on the rocking 75

member and is connected to the wave length instrumentality by a conductor 52 whereas contact 55 is connected to the wave length instrumentality through conductor 52'. By cooperation of the contacts 51 on the right hand side of the rocking member and the contact 53, the receiver is adjusted for tuning to a different wave length upon displacement of the rocking member to the right as by depression of push button 42. Compression spring 50 tends to force rocker 40 outwardly as viewed in Figure 7. However, spring 50 has no effect upon the axial displacement of the rocker 40. In other words, once rocker 40 is displaced axially to either the position wherein contact 54 engages contact 55 or the position wherein contact 51 engages contact 53, it remains in that position until it is moved out of it by depression of a push button which will cause it to move to the other position. Thus, assuming the key 41 is depressed and that because of the angular position of member 43, rocker bar 40 is moved over to the left, it will not return to its center position even though the top portion of member 43 falls below the lower surface of 46 when key 41 is depressed to its full extent. Upon depression of key 42, key 41 will be released due to rotation of rocker bar 40 against the force of spring 50 and rocker bar 40 is moved over to the right hand position due to the angular position of member 44 whereby engagement between contacts 54 and 55 is broken and contact 51 comes into engagement with contact 53.

Figs. 8, 9 and 10 show a third form of construction of the device according to the invention which comprises a number of press buttons 56 having each two bores 57 and 58 formed in it, it being possible, as is clearly seen in Fig. 9, to insert in them a stud 59 having a forked end 60 (Fig. 10). Each of the press buttons comprises a key shaft 61 adapted to cooperate in some manner with the tuning members of the set. Two rails 62 and 63 are arranged parallel with the row of press buttons and respectively in front of and at the back of the key shafts 61, said rails being interconnected by levers 64, 65 and 66, 67 respectively which are urged by springs. Under the action of the springs 68, 69 and 70, 71 respectively said rails will always be maintained in the position shown in Fig. 9 for the bus-bar 62. When one of the keys, in Figs. 8 and 9 the key 56', is forced-in the forked end 60 of the stud 59 in the forced-in key engages one of the rails, in the figure bus-bar 63, with the result that the levers by which this bus-bar is supported are rotated against the action of the spring and thus operate the wave length switch through the intermediary of a pull cable 72. The retracting springs ensure that when a key returns to its off-position the wave length switch also returns to its mid-position. In this system, a plurality of wave length ranges may also be selected without difficulty, such selection depending on the number of rails and the number of apertures in the keys.

Figs. 11 and 12 show a further form of construction of the device in which each of the keys 73, which are arranged on a row, has two adjacent apertures 74 and 75 formed in its shaft part. The stud 76 can be inserted in said apertures. The stud is designated in Fig. 11 for each of the keys by a black dot. At the side of the row of keys is arranged a slidable member 77 of which Fig. 12 is a cross-sectional view. This member has formed in it a number of apertures 78 which are tapered downwardly in the shape

of an edge. The member 77 has connected to it a lever 79 which cooperates with the switch arm 80 of the wave length switch 81. The slidable member 77 is maintained in its mid-position by two retracting springs 82 and 83. When one of the knobs is forced-in the stud 76 mounted in the knob will move the member 77, by means of its end, to the left or to the right according as the stud is arranged in the left hand or in the right hand aperture in the key shaft, with the result that the wave length switch arm 80 is moved to the left or to the right. The presence of the horizontal extensions of the apertures 78 ensure that this shifting of the member 77 will take place in an unhampered manner in spite of the presence of the studs 76 in the keys which are not forced-in. This embodiment may also be conceived of in such manner that the studs are not removable from the key shafts but are adjustable therein.

Fig. 13 shows a further form of construction of the wave length switch operating mechanism, the latter being formed by a scissor-shaped member the blades 84 and 85 of which are coupled in their movement by gear wheels 101 and 102 which engage each other. The blades 84 and 85 are possessed of projections arranged side by side. Thus, for example, the blade 84 in the embodiment of the figure carries projections 86, 87 and 88 and the blade 85 projections 89, 90 and 91. The keys 92, 93 and 94 arranged in front of the blades carry projections 95, 96 and 97 on their shafts. Comparatively small rotation of the keys about their shafts, for example through an angle of 30 degrees, permit these projections to be shifted in such manner that, on the keys concerned being forced-in, they engage a projection of the other scissor blade instead of that of the original blade with which they cooperated. The figure shows in addition that the shaft of the lower scissor blade is coupled to a lever 98 which operates the wave length switch (not shown) by means of a cable 99. Under the action of a spring (not shown) the scissor mechanism will always be maintained in the position shown, when none of the keys is forced-in. If, for example, one of the projections of the scissor-blade 85 is forced-in then the lever 98 of the wave length switch moves in the direction of the arrow A, the gear wheel 102 driving the gear wheel 101 and the scissor-blade 84 moving upwardly. If on the contrary one of the projections of the scissor blade 84 is operated then the scissor blade 84 is lowered with the result that the gear-wheel 101 rotates the gear wheel 102 and the lever 98 is moved in the direction of the arrow B.

It is also possible to arrange the device in such manner that in off-position of the keys the projections thereof are out of range of the upwardly-moving projections of the scissor blades.

I claim:

1. In radio receiving apparatus which is provided with an automatic tuning instrumentality including a plurality of station selecting push buttons and a wave band change-over switch for adjusting the receiver to tune over any one of a plurality of wave bands, at least one of said station selecting push buttons being rotatable about its axis to various different positions, single means operable upon operation of said push button for controlling the operation for said change-over switch and for holding said push button in a depressed position until the subsequent operation of another push button,

said means being arranged so as to operate the change-over switch so that the wave length to which the receiver is tuned upon depression of said push button when the push button is in 5 one of its angular positions is in one of said plurality of wave bands and to operate the change-over switch so that the wave length to which the receiver is tuned upon depression of said push button when the push button is in another of 10 its angular positions is in another of said plurality of wave bands.

2. The arrangement described in the next preceding claim characterized by that said single means comprises a rocker bar assembly which 15 upon depression of said push button is rocked about its axis and axially displaced in one direction when said push button is in said first named angular position, and in the other direction when said push button is in the second named angular 20 position.

3. In a tunable radio receiver which is provided with a push button tuning instrumentality and a selectively operable wave band change over switching means for adjusting the receiver 25 to tune to signals within any one of a plurality of wave bands, operable means for operating said switching means and for locking any depressed push button of said tuning instrumentality in a depressed position until the subsequent operation 30 of another push button of said tuning instrumentality, said operable means including an axially displaceable rocker bar capable of being rocked about its axis between a latching position and a releasing position and axially displaced from a position wherein the switching 35 means is operated so that said receiver is adjusted to tune to signals within one of said wave bands to a position wherein the switching means is operated so that the receiver is adjusted to 40 tune to signals within another of said wave bands, means for urging the rocker bar to its latching position, individual means for each of said push buttons each acting upon depression of its related push button to first rock said rocker 45 bar to its releasing position whereby any previously depressed push button is released, thereafter release the rocker bar whereby the rocker

bar returns to its latching position and finally cooperate with the rocker bar to hold its push button in a depressed position until released by the subsequent operation of another push button, at least one of said individual means being independently adjustable to various different positions and arranged so that upon depression of its push button it causes displacement of said rocker bar to an axial position depending upon the adjustment of said individual means. 10

4. In a tunable radio receiver which is provided with a push button tuning instrumentality and a selectively operable wave band change over switching means for adjusting the receiver to tune to signals within any one of a plurality of wave bands, operable means for operating said switching means and for locking any depressed push button of said tuning instrumentality in a depressed position until the subsequent operation of another push button of said tuning instrumentality, said operable means including a rocker bar arranged so as to be rocked about its axis between a latching position and a releasing position, said rocker bar being also axially displaceable between a position wherein the receiver 20 is adjusted to tune to signals within one of said wave bands and a position wherein the receiver is adjusted to tune to signals within another of said wave bands, means urging said rocker bar to its latching position, at least one of the push buttons of said tuning instrumentality being rotatable about its axis to different angular positions corresponding to said different wave bands, and means operable upon depression of said push button when said push button is in one of its angular positions, for axially displacing said rocker bar to the axial position, provided the rocker bar is not already in said position, which adjusts the receiver to tune to signals within the wave band corresponding to the angular position of said push button. 30
